D. E. HENNESSY,
VALVE DEVICE FOR HYDRAULIC JACKS.
APPLICATION FILED JULY 19, 1913.

1,189,815.

Patented July 4, 1916.

UNITED STATES PATENT OFFICE.

DANIEL E. HENNESSY, OF HOLYOKE, MASSACHUSETTS, ASSIGNOR, BY MESNE ASSIGNMENTS, TO HERBERT W. COWAN, J. LEWIS WYCKOFF, AND EDWARD N. WHITE, TRUSTEES.

VALVE DEVICE FOR HYDRAULIC JACKS.

1,189,815.

Specification of Letters Patent.

Patented July 4, 1916.

Application filed July 19, 1913. Serial No. 779,903.

To all whom it may concern:

Be it known that I, DANIEL E. HENNESSY, a citizen of the United States, residing at Holyoke, Massachusetts, have invented certain new and useful Improvements in Valve Devices for Hydraulic Jacks, of which the following is a clear, full, and exact description.

This invention relates to an improvement in hydraulic jacks, and has for its object the improvement of the same both as regards efficiency in operation and economy of construction.

In the preferred embodiment of my invention shown in the drawings, Figure 1 is a longitudinal section of such a jack, a portion of the operating handle and ram being cut away; Fig. 2 is a cross section through line 2-2 of Fig. 1; Fig. 3 is an end view looking from the left of Fig. 1; and Fig. 4 is a detail longitudinal section showing a modification.

Referring more particularly to the drawings, a cylindrical shell 1 preferably made of one integral piece has formed therein a pump chamber 3 and ram chamber 2, preferably arranged in tandem. A pump piston 5 is adapted to work back and forth in the pump chamber, and a ram 40 is adapted to work in the ram chamber 2. Preferably concentric with the shell 1 is formed an annular reservoir chamber 27 having outer wall 6, and it is understood that this reservoir chamber is adapted to contain the fluid for operating the jack whether it be air, water or any other similar means.

The pump piston 5 may be operated back and forth by any suitable lever arrangement, part of which is shown by lever 26 pivoted at 7 on bracket 12, and connected at 8 to the end 9 of said piston 5. The piston 5 is also preferably formed with a shoulder 10 for limiting its inward travel, either by abutting against the end of the shell 1 or against a stop 11 as shown in Figs. 1 and 3. The adjustable stop 11 in the present embodiment consists merely of a pivoted latch, which in its vertical position as shown in Fig. 1 is adapted to stop the inward travel of the pump piston before shoulder 10 reaches the shell 1 but which in its horizontal position shown by dotted lines in Fig. 3 allows said

pump piston 5 to move farther on into the pumping chamber for a purpose to be presently described.

Communication between the pumping chamber 3 and reservoir 27 is effected through port 19 and communication between pumping chamber and the ram chamber 2 is effected through port 13. Puppet valves 20 and 4 are arranged to be seated upon the ports 19 and 13 respectively.

In the present embodiment the preferable arrangement and construction of the puppet valves and their ports are as follows. Intermediate between the pumping chamber 3 and ram chamber 2 is arranged a body member 29 having cylindrical portions, one for fitting the inside of chamber 3 and one for fitting the inside of chamber 2. This intermediate body member 29 may be of one integral piece and preferably serves as a common cylinder head for both chambers 2 and 3. As seen the ports 19 and 13 are formed in this body member 29 and valve 4 has a stem 15 passing through said body member. At the pumping chamber side of the body member 29 is preferably formed a lever supporting portion 25, which also may be integral with said body member, and this supporting portion 25 as shown in Fig. 2 provides a guiding support for the stem 21 of valve 20 and the stem 15 of valve 4. A coil spring 22 surrounding valve stem 21 tends to seat the valve 20 in one direction, and a coil spring 16 surrounding stem 15 tends to seat the valve 4 in the opposite direction. Loosely mounted upon the support 25 is a lever or movable device 23 having a projecting boss 24 serving as a fulcrum therefor, which lever 23 engages beneath head 18 of valve stem 15 and head 30 of valve 21.

In Fig. 4 a modification of the device is shown in which the lever 23a has an extension 28 for engaging the piston 5 in advance of the head 18 of valve stem 15.

The operation of the jack is as follows: The pump piston 5 when worked back and forth by the lever 26 is adapted to suck the fluid from the reservoir 27 and force it into ram chamber 2 in the usual way for forcing out the ram, the valves 20 and 4 being automatically operated in an obvious manner.

In the embodiment of the invention shown in Fig. 1 the latch 11 is adjusted to the vertical position shown to limit the inward travel of the pump piston 5 so that said piston will not come in contact with either of the valve stems. When it is desired to release the ram and allow the load to lower under its own weight, the latch 11 is thrown to horizontal position shown by dotted lines in Fig. 3 and the pump piston 5 is thrust farther into its chamber so that the end of the same comes into positive engagement with the head 18 of valve stem 15 to open said valve 4 against its spring. At the same time lever 23 is rocked to move valve stem 21, 30, in the opposite direction and open valve 20. In this way both valves are operated by the inward movement of the pump piston so as to be open at the same time, and communication is opened from the ram chamber 2 through pump chamber 3, to reservoir 27, whereby the fluid flows back immediately and allows the load to lower.

In the embodiment of my invention shown in Fig. 1 the ram may be released by an adjustment of the separate latch-piece 11 and the operation of the piston as described, but in Fig. 4 a modification is shown in which no separate latch-piece is required and the ram may be released at any time by a continuous inward movement of the pump piston. To provide against releasing the ram at times when it is not desired, that is during the normal operation of the pump, a warning is given to the operator which will enable him to stop moving the piston inwardly too far. This warning is accomplished by opening the valve 20 prior to the opening of valve 4, whereby the inward movement of piston 5 causes first a slight release of pressure in front of the piston before the valve leading to the ram chamber has been opened. This preliminary release of pressure gives the operator warning that he has moved the piston 5 too far inwardly and that if he doesn't wish to release his ram he must immediately stop the further movement of his piston or move it in the other direction. The opening of valve 20 before the opening of valve 4 is accomplished in the present embodiment by providing lost motion between the end of the piston 5 and head 18 of valve stem 15. As shown, the lever piece 23^a is provided with an extension 28 above said head 18, whereby the piston 5 in its inward movement engages first extension 28 to rock lever 23^a and open valve 20, and later brings said extension into contact with head 18 to open valve 4.

It is to be understood that the embodiment of my invention herein shown and described is merely one practical construction of the same, and that equivalent variations may be

made therein without departing from the scope of my invention as expressed in the 65 claims.

What I claim is:

1. In a hydraulic jack in combination, a closed reservoir chamber containing a fluid, a closed pumping chamber, a closed ram 70 chamber, a communicating port between said reservoir and said pumping chamber, a communicating port between said pumping chamber and said ram chamber whereby the flow of contained fluid is confined within 75 said pumping, ram and reservoir chambers, a separate valve for each port movable in opposite directions for being opened, manually operated means for opening both of said valves together for giving communication 80 between said ram chamber and said reservoir, comprising a rocking member for transmitting movement to one of said valves in a reverse direction to that of the other valve.

2. In a hydraulic jack in combination, a 85 pumping chamber having a piston therein, inlet and outlet ports at one end of said pumping chamber opposite the end of said piston, a separate valve for each port located directly in front of said piston, and means 90 for opening both of said valves by a positive engagement with said pump piston when the same is moved in one direction.

3. In a hydraulic jack in combination, a pumping chamber having a piston therein, 95 inlet and outlet ports at one end of said pumping chamber opposite the end of said piston, a separate valve for each port, and means for opening both of said valves together by a positive engagement with the 100 inner end of said pump piston.

4. In a hydraulic jack in combination, a pumping chamber having a piston therein, inlet and outlet ports at one end of said pumping chamber opposite the end of said 105 piston, a separate valve for each port, and means for opening both of said valves by a positive engagement with said pump piston when the same is moved in one direction, comprising a rocking member acting to 110 transmit movement to one of said valves in a reverse direction to that of the other valve.

5. In a hydraulic jack in combination, a pumping chamber and a ram chamber arranged in tandem, said pumping chamber 115 having a piston adapted to work therein, inlet and outlet ports at one end of said pumping chamber opposite the end of said piston, a separate valve for each port located directly in front of said piston, and means 120 for opening both of said valves by a positive engagement with said pumping piston when the same is moved in one direction.

6. A hydraulic jack having a valve device 125 removably mounted therein, comprising a body member with two separate ports

formed therein, separate valves carried on said body member for closing said ports, and a rocking member for transmitting movement to one of said valves in a reverse 5 direction to that of the other valve.

7. A valve device for hydraulic jacks and the like, comprising a body member with two separate ports therein, separate valves for closing said ports, stems on said valves

10 slidably mounted on said body member, a lever support and a lever rocking on said support and engaging said valve stems for transmitting movement to one of said valves in a reverse direction to that of the other 15 valve.

8. In a hydraulic jack in combination, an integral cylindrical shell having a pumping chamber and a ram chamber arranged in tandem, a removable intermediate body 20 member serving as a common cylinder head for both said pumping and ram chambers, inlet and outlet ports for said pumping chamber, separate valves for said ports, and means for opening both of said valves together 25 by said piston when the same is moved in one direction.

9. In a hydraulic jack in combination, an integral cylindrical shell having a pumping chamber and a ram chamber arranged in 30 tandem, a removable intermediate body member serving as a common cylinder head for both said pumping and ram chambers, inlet and outlet ports for said pumping chamber formed in said body member, separate 35 valves for said ports, and means for opening both of said valves together by the inner end of said piston.

10. A hydraulic jack having in combination, a reservoir chamber, a pumping chamber, a ram chamber, a communicating port 40 between said reservoir and said pumping chamber, a communicating port between said pumping chamber and said ram chamber, a working fluid confined in said jack, a pump piston working in said pumping chamber, valves for said ports arranged to be opened alternately by the normal pumping action of said pump piston to transfer fluid from said reservoir to said ram 45 chamber, and an independently movable device adapted when operated to open both of said valves so that said valves will be open at the same time in order to allow fluid to flow back from said ram chamber to said reservoir.

11. A hydraulic jack having in combination, a reservoir chamber, a pumping chamber, a ram chamber, a communicating port 50 between said reservoir and said pumping chamber, a communicating port between said pumping chamber and said ram chamber, a pump piston working in said pumping chamber, valves for said ports arranged to

be opened alternately by the normal pumping action of said pump piston to transfer 65 fluid from said reservoir to said ram chamber and a movable device connected with both of said valves adapted when operated to open both of said valves so that said valves will be open at the same time in order 70 to allow fluid to flow back from said ram chamber.

12. A hydraulic jack having in combination, a reservoir chamber, a pumping chamber, a ram chamber, a communicating port 75 between said reservoir and said pumping chamber, a communicating port between said pumping chamber and said ram chamber, a working fluid confined in said jack, a pump piston working in said pumping 80 chamber, valves for said ports arranged to be opened alternately by the normal pumping action of said pump piston to transfer fluid from said reservoir to said ram chamber and an independently movable device 85 adapted when operated to open both of said valves so that said valves will be open at the same time in order to allow fluid to flow back from said ram chamber to said reservoir and manually controlled means for 90 operating said movable device to release said ram.

13. A hydraulic jack having in combination, a reservoir chamber, a ram chamber, and a pumping chamber, an inlet port from 95 said reservoir to said pumping chamber, an outlet port from said pumping chamber to said ram chamber, a working fluid confined in said jack, a pump piston working in said pumping chamber, an inlet valve and 100 an outlet valve for said respective ports arranged to be opened alternately in pumping fluid from said reservoir to said ram chamber and means operated by the inward movement of said piston beyond its normal 105 expelling stroke to open both of said valves so that said valves will both be open at the same time to allow fluid to flow back from said ram chamber to said reservoir, said means being constructed and arranged to 110 open said inlet valve slightly in advance of said outlet valve.

14. A hydraulic jack having, in combination, a reservoir chamber, a pumping chamber, a ram chamber, communicating ports 115 respectively between said reservoir and pumping chambers and between said pumping and ram chambers, a pump piston working in said pumping chamber, valves for said ports, and valve opening means separate from the piston but arranged to be engaged and operated thereby and constructed to open both of said valves in a predetermined order.

15. A hydraulic jack having, in combination, a reservoir chamber, a pumping cham-

ber, a ram chamber, communicating ports respectively between said reservoir and pumping chambers and between said pumping and ram chambers, a pump piston working in said pumping chamber, valves for said ports, and valve opening means separate from the piston but arranged to be engaged and operated thereby and constructed to open the valve between the res-

ervoir and pumping chambers before it operates to open the valve between the pumping and ram chambers. 10

Signed at Holyoke, Mass., this 16 day of July, 1913.
